(57) **CLAIM**

We claim the ornamental design for a tooth for mechanical equipment, as shown and described.

DESCRIPTION

FIG. 1 is a top perspective view showing our new design for a tooth;

FIG. 2 is a bottom perspective view thereof;

FIG. 3 is a top view thereof;

FIG. 4 is a bottom view thereof; and,

FIG. 5 is a front view thereof, wherein the back view is the same, and the right and left sides are the same.

The tooth can be used for a circular saw or mower drum.
